RENDERING MACHINE

Filed Sept. 25, 1929

UNITED STATES PATENT OFFICE

1,973,928

RENDERING MACHINE

Christopher Offenhauser, Philadelphia, Pa.

Application September 25, 1929, Serial No. 395,010

3 Claims. (Cl. 87—13)

One of the objects of this invention is to devise a novel rendering machine wherein a minimum amount of steam is employed for the rendering operation. It has heretofore been customary in devices of this character to employ a single steam-jacket around the rendering tank through which steam circulates.

In accordance with this invention I employ exterior of the inner steam-jacket an outer steam-jacket which is in valve controlled communication with the rendering chamber of the rendering tank so that the steam and vapors in the rendering tank can be withdrawn through the outer steam-jacket.

15 A further object of the invention is to devise novel means for stirring and agitating the material being rendered in the form of a novel construction of helically arranged paddles with means for causing them to revolve in either a forward or a reverse direction.

20 A further object of this invention is to devise a novel rendering machine wherein in the same machine the material can be subjected to both heat and pressure so that a greater volume of the oil is separated in the same machine.

25 A further object is to devise a novel rendering machine wherein the material is first subjected to the action of heat while being fed in one direction and wherein when the material is fed in the opposite direction it passes to a pressure extracting mechanism in the form of a compressor screw or worm.

With the above and other objects in view, as will hereinafter more clearly appear, my invention comprehends a novel rendering machine.

It further comprehends a novel rendering machine having a plurality of steam-jackets surrounding the rendering tank with one of said steam-jackets in communication with the chamber of the rendering tank.

40 It further comprehends a novel rendering machine wherein novel means are employed to agitate and break-up the material such means adapted to be driven in either a forward or reverse direction.

45 It further comprehends a novel rendering machine wherein novel means are employed to maintain the material at the proper temperature and to agitate it during the action of rendering and at the same time to cause the movement of the material towards one end of the tank, provision being made for reversing the direction of such movement to cause the material to feed from the tank to an outlet in which the material may be compressed to effect the extraction of oils and fats therefrom.

50 Other novel features of construction and advantage will hereinafter clearly appear in the detailed description and the appended claims.

For the purpose of illustrating the invention, I have shown in the accompanying drawing typical embodiments of it, which, in practice, will give reliable and satisfactory results. It is, however, to be understood that these embodiments are typical only and that the various instrumentalities of which my invention consists can be variously arranged and organized, and the invention is not limited to the precise arrangement and organization of these instrumentalities as herein set forth.

Figure 1 is a side elevation partly diagrammatic of a rendering machine embodying my invention.

Figure 2 is a front elevation of one of the paddles.

Figure 3 is an end elevation of the paddle seen in Figure 2.

Figure 4 is a side elevation of another form of pressing mechanism embodying the invention.

Similar numerals of reference indicate corresponding parts.

Referring to the drawing:—

The rendering machine is driven by means of a prime mover 1 which is preferably an electric motor. The shaft of the motor is provided with a reversing mechanism 2 and forms an operative connection with the shaft 3 on which is mounted a pulley 4 around which passes a belt 5 which latter also passes around a pulley 6 on an agitator shaft 7. This agitator shaft 7 is suitably journalled in bearings 8 and passes through the chamber 9 of a rendering tank 10. The rendering tank 10 is provided with a controllable filling opening 11 through which the material to be treated is introduced into the chamber 9 of the rendering tank. This opening 11 is provided with a closure 12 of any desired character.

90 The agitator shaft 7 has mounted thereon the hubs 13 which are provided with the stems 14 to which are connected the plates 15 which are preferably hardened steel plates having a knife edge and removably connected to the outer ends or heads of the stems 14 by means of fastening devices 16.

95 The rendering tank 10 is surrounded by an inner steam-jacket 17 and by an outer steam-jacket 18. A steam pipe 19 connected with a source of steam supply leads to the inner steam-jacket 17 and is provided with a controlling valve 20. A branch steam conduit 21 leads from the inlet steam line 19 and communicates with the outer steam-jacket 18 which is provided with a controlling valve 22. It will thus be seen that live or exhaust steam can be introduced into either the inner and outer steam-jacket or into both of such steam-jackets.

100 The chamber 9 communicates by means of a conduit 23 with the upper end of the outer steam-jacket 18 and is provided with a controlling valve 24 and also if desired with a one-way valve 25.

The inner steam-jacket 17 is provided with an outlet conduit 26 which communicates with the outer steam-jacket 18.

27 designates a conduit leading from the outer steam-jacket 18 and adapted to be connected to a vacuum or suction pump leading to a condenser in the usual and conventional manner. The tank 10 is provided with an outlet 28 which leads to the chamber 29 of pressing mechanism 30. The shaft 10 3 which is journalled in suitable bearings 31 has its forward end extending into the outlet 28 and adapted to be connected with a pressure screw or worm 32 which extends into the removable sleeve 33 of the pressing mechanism and at its forward 15 end it converges as at 34, in order to be in close proximity to the inner wall of the converging end 35 of the sleeve 33. This sleeve is provided with a desired number of ports 36. The pressure screw 32 is detachably connected with the cross bar 37 of the shaft 3 so that when the closure 38 is removed the sleeve 33 and also the pressure screw 32 may be removed if desired. The closure 38 is in threaded engagement with the outer end of the pressing mechanism and has connected to it in any desired manner a closure 39 provided with a pressing cone 40 which extends into the closure 38 thus forming a chamber 41 through which the pressed material is withdrawn. A steam line 42 discharges into the chamber of the pressing mechanism 30 and the oil and fat are withdrawn through the conduit 43.

Referring now more particularly to Figure 4 I have shown in this figure a pressing mechanism in which the pressing screw 46 is straight and the sleeve 47 corresponding to the sleeve 33 also has a straight bore, it being apparent that otherwise the operation would be the same as that of the construction shown in Figure 1.

In the operation, the chamber 9 is charged with 43 the material to be rendered through the filling opening 11 and the motor 1 is started. The reversing mechanism 2 is actuated to cause the material to feed toward the left hand end of the rendering tank so that the shaft 7 and the shaft 45 3 are revoluble in a counter-clockwise direction. The valve 20 is opened admitting steam to the inner steam-jacket 17 and if desired the valve 22 is opened so that steam will also be admitted through the branch conduit 21 into the outer steam-jacket 18.

Assuming now that the motor is in operation, driving the parts in a counter-clockwise direction, the material which is being subjected to the action of the steam is also being stirred and 55 agitated by the paddles 15. The steam and vapor in the rendering tank caused by the heating of the material escapes through the valve controlled conduit 23 into the outer steam-jacket 18 and the steam from the inner steam-jacket 17 is vented by a conduit 26 to the outer steam-jacket 18 from which latter it is withdrawn through the suction pipe 27. As soon as the proper rendering action, due to the heat, has been effected, the reversing mechanism 2 is actuated to cause the moving 60 parts to revolve in a clockwise direction whereupon the material being rendered in the chamber 9 is fed to the outlet 28 where it is moved forwardly by the compressor screw 32 and is compressed in the sleeve 33, the oils and fats being extracted and passing through the ports 36.

The cone 40 at its inner end is slightly smaller than the diameter of the outlet of the worm

sleeve 33 so that as the material passes to the cone a very effective pressing action is accomplished. The compressed material discharges through the opening 41.

I have found that in accordance with this invention a large economy in steam consumption is obtained and also a very large proportion of oil and fat is extracted in a single heating and pressing operation.

Special attention is directed to the form of pressure screw or worm employed with the pressing mechanism. It is provided with a helically interrupted blade so that while the pressing operation will be progressive it will be intermittent.

The outlet of the rendering chamber 9 is below the bottom of the tank so that material will feed downwardly by gravity to the outlet and if it is not desired to compress the material it will be apparent that this outlet will serve as an automatic unloader either with or without the pressure screw 32. The sleeve 33 if employed is preferably perforated throughout its length in order that the oil may pass therethrough.

The conduit 23 leading from the chamber of the rendering tank 9 is preferably provided with a valve controlled branch conduit 49 which, if desired, may be connected to a vacuum pump or other suction device to withdraw the vapors from the rendering tank.

It will now be apparent that I have devised a new and useful rendering machine which embodies the features of advantage enumerated as desirable in the statement of the invention and the above description, and while I have, in the present instance, shown and described preferred embodiments thereof which will give in practice satisfactory and reliable results, it is to be understood that these embodiments are susceptible of modification in various particulars without departing from the spirit or scope of the invention or sacrificing any of its advantages.

Having thus described my invention what I claim as new and desire to secure by Letters Patent, is:—

1. In a rendering machine, a rendering tank 120 having an inner steam-jacket surrounding its outer periphery, an outer steam-jacket surrounding the inner steam-jacket, a valve controlled conduit communicating with said tank and outer steam-jacket, a controllable steam inlet to one of said steam-jackets, and a suction pump outlet from one of said steam-jackets.

2. In a rendering machine, a rendering tank having an inner steam-jacket surrounding its outer periphery, an outer steam-jacket surrounding the inner steam-jacket, a valve controlled conduit communicating with said tank and outer steam-jacket, a controllable steam inlet to one of said steam-jackets, a suction pump outlet from one of said steam-jackets, and means to agitate the material in said tank.

3. In a rendering machine, a steam-heated rendering tank having a rendering chamber, a double steam-jacket surrounding said chamber, a valve controlled communication with each of said water jackets, a valve controlled outlet leading from said chamber to one of said steam-jackets, and a valve controlled conduit communicating with said chamber and adapted to be connected to a vacuum pump.
